UNITED STATES PATENT OFFICE.

JOHN HOULEHAN, OF EAST ELY, NEVADA.

MECHANICAL MOVEMENT.

1,209,708.

Specification of Letters Patent. Patented Dec. 26, 1916.

Application filed April 10, 1916. Serial No. 90,228.

To all whom it may concern:

Be it known that I, JOHN HOULEHAN, a citizen of the United States, residing at East Ely, in the county of White Pine and State of Nevada, have invented a new and useful Mechanical Movement, of which the following is a specification.

The device forming the subject matter of this application is an engine and the invention aims to provide novel means whereby at each rotation of the shaft of the engine, two strokes will be brought about in each of two pitmen which form an operative connection between the piston of the engine and the shaft thereof.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings: Figure 1 shows in top plan, an engine embodying the present invention, parts being broken away; Fig. 2 is a side elevation of the structure shown in Fig. 1, the parts being in the positions which they will assume when a compression stroke is about to be made; Fig. 3 is a diagrammatic view showing in side elevation, the parts in the positions which they will assume when an explosion stroke is about to be made; Fig. 4 is a diagrammatic view illustrating the parts in the positions which they will assume when a scouring stroke is about to be made; Fig. 5 is a diagrammatic view showing the parts in the positions which they will assume when a suction stroke is about to be made; Fig. 6 is a fragmental cross section showing portions of the disks, the engine shaft, one of the pitmen being shown in part; Fig. 7 is a diagrammatic view showing the device forming the subject matter of this application coupled up with a four-cylinder four-cycle engine; and Fig. 8 is a diagrammatic view

showing the device forming the subject matter of this application coupled up with a two-cylinder two-cycle engine.

In carrying out the present invention there is provided a base 1 supporting a bed 2 carrying a cylinder 3 in which works a piston 4. Upstanding from the base 1 are standards 5 carrying bearings 6 in which is journaled a shaft 7 provided with a fly wheel 8. Mounted on and secured to the shaft 7 between the standards 5 is an intermediate disk 9. In one side of the intermediate disk 9 there is fashioned a lenticular groove 25 comprising branches 26 and 27 and provided at its ends with seats 28 and 29. In the opposite side of the intermediate disk 9 there is formed a lenticular groove 30 comprising branches 31 and 32, and having seats 33 and 34 at its ends. The axes of the grooves 25 and 30, that is, the lines which connect the pointed ends, are disposed at right angles to each other. Secured to the shaft 7 is a disk 39. The disk 39 has upon its inner face, a groove 40 shaped like the groove 25 in the intermediate disk 9, and alined therewith. Secured to the shaft 7 is a disk 41. In the inner face of the disk 41 there is a groove 42 shaped like the groove 30 in the intermediate disk 9, and alined with the groove 30.

The numeral 35 designates a pitman carrying a roller 38 adapted to traverse the groove 25. The pitman 35 carries also a roller 43 adapted to traverse the groove 40.

At 36 there appears a pitman provided with a roller 37 adapted to traverse the groove 30, the pitman 36 being equipped with a roller 44 adapted to traverse the groove 42. The pitmen 36 and 35 are pivoted as shown at 45 to the piston 4.

The disk and pitman construction hereinbefore described may be used upon an engine of any desired sort but in Figs. 1, 2, 3, 4 and 5 a single-cylinder four-cycle internal combustion engine has been shown, by way of illustration merely. When the structure is employed in connection with single-cylinder four-cycle internal combustion engine, the operation is as follows:—

In Fig. 2, the parts are in the positions they assume when a compression stroke in the direction of the arrow A is about to be made, the disks rotating in the direction of

the arrow C. During the compression stroke and while the disks are turning through an arc of 90°, the roller pitman 36 is engaged in the seat 34 of the groove 30, and the roller 38 on the end of the pitman 35 rides in the branch 27 of the groove 25 toward the seat 29 of the groove 25.

In Fig. 3, the parts are in the positions they assume when an explosion stroke in 10 the direction of the arrow B is about to be made, the disks rotating in the direction of the arrow C. During the explosion stroke and while the disks are turning through an arc of 90°, the roller 38 on the end of the pitman 35 is engaged in the seat 29 of the groove 25, and the roller 37 on the end of the pitman 36 rides in the branch 31 of the groove 30 toward the seat 33 of the groove 30.

20 In Fig. 4, the parts are in the positions they assume when a scouring stroke in the direction of the arrow A is about to be made, the disks rotating in the direction of the arrow C. During this stroke and while the 25 disks are turning through an arc of 90°, the roller 37 on the end of the pitman 36 is engaged in the seat 33 of the groove 30, and the roller 38 on the end of the pitman 35 rides in the branch 26 of the groove 25 30 toward the seat 28 of the groove 25.

In Fig. 5, the parts are in the positions they assume when a suction stroke in the direction of the arrow B is about to be made, the disks rotating in the direction of the 35 arrow C. During the suction stroke and while the disks are turning through an arc of 90°, the roller 38 on the end of the pitman 35 is engaged in the seat 28 of the groove 25, and the roller 37 on the end of the 40 pitman 36 rides in the branch 32 of the groove 30 toward the seat 34 of the groove 30.

It will be obvious that if the direction of 45 rotation of the shaft 7 and the disks is reversed, the operation above described will be changed somewhat. Further, the location of the exhaust port and the timing of the inlet and exhaust valves, may alter the above described operation somewhat, but the operation above set forth is one which may take

place and it will serve to illustrate one of 50 the many operations which may occur.

The invention, of course, is not confined to be used in connection with an internal combustion engine, or with a single-cylinder four-cycle internal combustion engine of the 55 sort above described.

In Fig. 7 of the drawings, there is shown diagrammatically, a four-cylinder four-cycle internal combustion engine, the cylinders of which appear at 46, the numeral 47 denoting the pistons. The pitmen are shown at 48 and the intermediate disks appear at 49, the same being constructed as hereinbefore described.

In Fig. 8 of the drawings, the numeral 50 65 designates the cylinders of a two-cycle two-cylinder internal combustion engine, the pistons appearing at 51, the pitmen at 52 and 53, and the intermediate disks at 54, the same being of the sort hereinbefore set forth. 70

Having thus described the invention, what is claimed is:—

1. In an engine, a cylinder; a piston working in the cylinder; a disk supported for rotation and provided with lenticular 75 guides, the axes of the guides being at right angles to each other; and pitmen, the inner ends of which are pivoted to the piston, the outer ends of which are provided with means for traversing the respective guides. 80

2. In an engine, a cylinder; a piston working in the cylinder; a disk supported for rotation and provided with lenticular guides having seats at their ends, the axes of the guides being disposed at right angles to each other; and pitmen, the inner ends of which are pivoted to the piston, the outer ends of the pitmen being provided with means for traversing the guides, respectively, and for engaging alternately in the seats of the 85 90 respective guides.

In testimony that I claim the foregoing as my own, I have hereto affixed my signature in the presence of two witnesses.

JOHN HOULEHAN.
